UNITED STATES PATENT OFFICE.

HILDUR C. LANGE, OF NEW YORK, N. Y.

DESIGN FOR A DOLL.

Application filed April 8, 1922. Serial No. 1,648. Term of patent 3½ years.

To all whom it may concern:

Be it known that I, HILDUR C. LANGE, a citizen of the United States, residing at No. 41 West 35th Street, in the city and county of New York and State of New York, have invented a new, original, and ornamental Design for Dolls, of which the following is a specification, reference being had to the accompanying drawing, forming part thereof,

The figure is a front view of a doll, showing my new design.

I claim:

The ornamental design for a doll, as shown.

Signed at New York, in the county of New York, and State of New York, this 7th day of April, 1922.

HILDUR C. LANGE.
